UNITED STATES PATENT OFFICE.

THOMAS F. CARBERY, OF ST. LOUIS, MISSOURI, AND THOMAS A. STAINTHORP, OF DUPO, ILLINOIS.

BOILER-FEED-WATER HEATER.

Application filed March 17, 1923. Serial No. 625,920.

To all whom it may concern:

Be it known that we, THOMAS F. CARBERY, of the city of St. Louis, State of Missouri, and THOMAS A. STAINTHORP, of Dupo, county 5 of St. Clair, State of Illinois, both citizens of the United States, have invented new and useful Improvements in Boiler-Feed-Water Heaters, of which the following is a specification.

10 Our invention relates to new and useful improvements in boiler feed water heaters and particularly to that class which utilizes heat from the waste gases resulting from combustion as they pass through the smoke 15 box of the boiler and up the chimney or stack, together with the heat from exhaust steam. It has for its object the provision of apparatus of the character designated which shall be simple of construction, shall 20 subject the feed water passing therethrough both to the heat of the gases within the smoke box and those passing out the chimney or stack, together with the heat from exhaust steam, and which shall cause a rapid 25 circulation of the feed water while passing through the heater insuring its contact with all the heating surfaces thereof.

It has been proposed, heretofore, to utilize the heat from waste gases together with the 30 heat from exhaust steam, while passing out the chimney or stack of the boiler, for heating the boiler feed water. In the methods proposed however serious difficulties have been encountered in providing a sufficient 35 heating surface, without at the same time, so obstructing the chimney or smoke box of the boiler as to interfere with the passage of the gases therethrough and thus interfere with the steaming qualities of the boiler.

40 We have overcome the aforementioned difficulties in our invention and have provided a feed water heater simple in design, cheap of construction and maintenance, with no moving parts, occupying little more space 45 in the smoke box than is already occupied and not interfering with the operation of any part of the boiler or obstructing the view of the enginemen where applied to a locomotive boiler.

50 Broadly, our invention consists in adapting the smoke stack and lift pipe (sometimes called the inside stack) of a boiler for feed water heating. More specifically this is done by constructing the smoke stack and lift 55 pipe in one piece having an outer and inner

wall with an annular space between them. Within the annular space is a spiral passage providing for a rapid circulation of the water within the heater. For the purpose of providing more heating surface and 60 consequent greater efficiency, this spiral passage is formed by coils of a pipe for exhaust steam, the pipe being of such diameter as to fit snugly between the outer and inner walls 65 of the feed water heater.

In the single figure of our drawing we have shown a side elevation of our device applied to a locomotive with some of the parts broken away to more clearly indicate the construction thereof. 70

In the accompanying drawing which shows the preferable construction, 1 represents a locomotive boiler having tubes 2 through which the products of combustion pass on their way through the boiler, a deflector 3 regulating the passage of the gases through the tubes 2, a cylinder 4 in which the piston driving the locomotive is actuated, an exhaust nozzle 5 through which exhaust steam from the cylinder passes, creating a draft through the tubes 2 and a smoke box 6 having an outlet 7 through which the products of combustion escape. 80

Hitherto the outlet 7 has been provided with an ordinary smoke stack extending 85 above the smokebox 6 while inside said smokebox a lift pipe or petticoat pipe has been attached to the base of the smoke stack to better direct the exhaust steam and products of combustion up the stack and improve the steaming qualities of the locomotive. This arrangement proved entirely satisfactory so far as the object it was to accomplish was concerned, but in accomplishing this object the products of combustion 90 were allowed to escape at a temperature around 750° F. their heat being entirely lost. Furthermore, the exhaust steam, after performing its work in the cylinders of the engine, was allowed to escape without taking 100 any advantage of the heat which it contained.

In the outlet 7 we have placed the feed water heater which we have invented, taking the place of the smoke stack and lift 105 pipe or petticoat pipe hitherto used. We prefer to make this feed water heater conform, as far as is practicable, substantially to the dimensions of the smoke stack and lift pipe which experience has proved 110

proper on each particular class of locomotive. As applied to a modern locomotive the greater portion of the feed water heater (approximately two thirds) will extend 5 down into the smoke box 6. Lagging 8 is placed around that portion of the heater extending above the smokebox to prevent a loss of heat from that portion through radiation.

10 The feed water heater is substantially cylindrical in form so as to be self supporting, though by providing proper staying, any other suitable form may be employed. It is constructed with an inner wall 9, which 15 surrounds the outlet 7 through which the exhaust steam and products of combustion pass, and an outer wall 10 larger in diameter than the inner wall, surrounding the inner wall, thus forming an annular space 11 between the two. The two walls are held apart and the annular space between them is closed at the upper end by a ring 12 and at the lower end by a ring 13. The inner 20 and outer walls 9 and 10 and the ends 12 and 13 are constructed of suitable material 25 of sufficient strength to withstand the pressure in the boiler. The whole arrangement is securely fastened to the smokebox by a ring 14 which is attached to the outer wall 30 10 of the feed water heater and to the top of the smokebox 6.

Inside the annular space 11 is disposed a spiral passage 15 which forces the boiler feed water in its passage to the boiler to 35 travel around and upward in its passage through the feed water heater causing a rapid circulation of the water within the heater and insuring that each particle of water in its passage through the heater is 40 exposed to substantially all of the heating surface. This feature is very important, as the amount of heat absorbed by water in a feed water heater depends, mainly, on a rapid circulation and agitation of the water 45 within the heater and its exposure to the greatest possible area of heating surface. The rapid circulation of the water also sets up a scouring action causing the feed water heater to be self cleaning and preventing an 50 accumulation of mud and scale within the heater.

The spiral passage 15 preferably is formed by coils of a pipe 16 co-operating with the outer and inner walls of the feed water heater. This pipe is of such diameter as to 55 fit snugly between the outer and inner walls of the feed water heater substantially preventing water from passing between the pipe and the walls thus causing it to follow the 60 spiral passage between the coils. The distance between the coils (viz. the pitch), is substantially uniform from end to end of the heater and is limited to permit, without restricting, a free flow of water to the boiler. 65 An exhaust steam pipe 17 extending through

the wall 10 of the feed water heater preferably is connected to the coil near the top of the feed water heater as shown in the drawing at 18. In this way the steam in imparting its heat to the water within the feed water heater will condense and form water which can flow by gravity downward through the coils and out at the lower end as shown in the drawing at 19. This prevents back pressure from forming within the coils, and permits the return of the water of condensation to the tender or water supply of the boiler if desired, whereby the temperature of such water supply may be raised.

While we have shown the pipe 17 as being connected to the exhaust pipe 5 from the cylinders, it is to be understood that this is for the purpose of illustration only. The exhaust steam employed in the coil 16 may be taken from any convenient source, many of which will suggest themselves to those skilled in the art.

In the drawing, a pipe 20 is shown having a connection 21 for admitting the boiler feed water into the feed water heater. A delivery pipe 22 is connected to the top of the feed water heater at 23 which pipe conveys the feed water, after having passed through the heater, backward to a boiler check valve 24 where it enters the boiler.

When the locomotive is being operated, exhaust steam from its cylinders passes through the exhaust nozzle 5 and is expelled up through the outlet 7 in the feed water heater. This creates a partial vacuum in the smoke box 6 which draws the products of combustion through the tubes 2 at a very high velocity. After these products of combustion pass through the tubes they travel downward and under the deflector 3 which imparts to them a whirling motion causing them to be violently whirled around in the smokebox until entrained and expelled by the exhaust steam passing upward through the outlet 7 in the feed water heater. The violent motion of the products of combustion within the smokebox causes them to impinge against the outer wall 10 of the feed water heater. Thus, the feed water heater has direct contact with the products of combustion within the smokebox. At the same time the exhaust steam from the nozzle 5 mingled with escaping products of combustion is being forced at a very high velocity against the inner wall 9 which surrounds the opening through the feed water heater.

In the operation of the feed water heater, boiler feed water (which may be supplied by a pump or any other suitable means) is conveyed through the pipe 20 into the spiral passage 15 formed by the exhaust steam pipe within the annular space between the heater walls 9 and 10 and is forced upward and around the spiral passage. This feed water

absorbs heat from the hot gases in the smokebox through that portion of the outer wall 10 of the heater that extends into the smokebox and through the inner wall 9 of the heater from the exhaust steam and products of combustion in their escape to the atmosphere. At the same time heat is absorbed from the exhaust steam coils 16 which form the spiral passage within the 10 heater in co-operation with the walls of the heater. As applied to a modern locomotive having a boiler 72 inches in diameter and a feed water heater having an inside diameter of 18 inches, we have found that the feed 15 water in its passage through the feed water heater travels over 100 feet during which time it is kept in constant agitation and is exposed to all the heating surfaces of the feed water heater. By this means water 20 introduced into the heater at a temperature of around 70° F. is delivered to the boiler at a temperature approximating that of the exhaust steam passing through the coils of pipe within the heater, thus effecting a 25 marked saving in fuel which would otherwise be required to heat the water after it entered the boiler.

While the construction of our invention as heretofore described is, at present, the approved form, the claims herein made are intended to cover any equivalent construction.

We claim as our invention:

1. A feed water heater for a locomotive boiler having a smoke box through which the gaseous products of combustion pass, comprising a smoke stack disposed within the smoke box and extending outwardly from the interior thereof, an outer wall surrounding the smoke stack and forming therewith an annular chamber, a heating coil disposed within the annular chamber and forming with the walls thereof a spiral passage within the annular chamber, and means for forcing the boiler feed water 45 through said spiral passage.

2. A feed water heater for a locomotive boiler having a smoke box through which the gaseous products of combustion and the locomotive exhaust passes, comprising a 50 smoke stack disposed within the smoke box and extending outwardly from the interior thereof, an outer wall surrounding the smoke stack and forming therewith an annular chamber, a heating coil so disposed 55 within the annular chamber as to form with the walls thereof a spiral passage within the annular chamber, and means for forcing the boiler feed water through said spiral passage, said spiral passage being so proportioned as to provide a rapid circulation of the feed water passing therethrough.

3. A feed water heater for a locomotive boiler having a smoke box through which the gaseous products of combustion pass, 60 comprising a smoke stack disposed within

the smoke box and extending outwardly from the interior thereof, an outer wall surrounding the smoke stack and forming therewith an annular chamber, a heating coil disposed within the annular chamber 70 and forming with the walls thereof a spiral passage within the annular chamber, means for forcing the boiler feed water through said spiral passage, said spiral passage being so proportioned as to provide a rapid circulation of the feed water passing therethrough, and means for passing a heating medium through said heating coil. 75

4. In a feed water heater for a locomotive boiler having a smoke box through which the gaseous products of combustion pass, the combination of a smoke stack extending through the shell of the smoke box and having the major portion thereof enclosed within the smoke box, an outer wall surrounding the smoke stack and forming therewith an annular chamber, a heating coil within the annular chamber, means for forcing boiler feed water through said annular chamber, an exhaust pipe, and means for conveying exhaust steam from the exhaust pipe to the heating coil. 80

5. In a feed water heater for a locomotive boiler having a smoke box through which the gaseous products of combustion pass, the combination of a smoke stack extending through the shell of the smoke box and having the major portion thereof enclosed within the smoke box, an outer wall surrounding the smoke stack and forming therewith an annular chamber, a heating coil snugly fitting between the walls of the annular chamber and forming therewith a spiral passage, means for forcing boiler feed water through said spiral passage, an exhaust pipe in alignment with the smoke stack, and a conduit for conveying exhaust steam from the exhaust pipe to the heating coil. 95

6. In a feed water heater for a locomotive boiler having a smoke box through which the gaseous products of combustion pass, the combination of a smoke stack extending through the shell of the smoke box and having the major portion thereof enclosed within the smoke box, an outer wall surrounding the smoke stack and forming therewith an annular chamber, a heating coil snugly fitting between the walls of the annular chamber and forming therewith a spiral passage, means for forcing boiler feed water through said spiral passage, an exhaust pipe in alignment with the smoke stack, and a conduit for conveying exhaust steam from the exhaust pipe to the heating coil and so connected to the heating coil as to pass the heating medium therethrough in a direction opposite to the direction of flow of the feed water. 100

7. In a feed water heater for a locomotive 110

boiler having a smoke box through which the gaseous products of combustion pass, the combination of a smoke stack extending through the shell of the smoke box and having the major portion thereof enclosed within the smoke box, an outer wall surrounding the smoke stack and forming therewith an annular chamber, a heating coil within the annular chamber and forming with the walls 10 thereof a spiral passage, means for forcing boiler feed water through said spiral passage from the lower part of the smoke

stack upwardly, an exhaust pipe in alignment with the smoke stack, a conduit for conveying exhaust steam from the exhaust 15 pipe to the heating coil at a point near the upper end of the smoke stack, and a conduit connected to the heating coil near the lower end of the smoke stack for conveying steam and condensate from the heating coil. 20

Signed at St. Louis, State of Missouri, this 14th day of March 1923.
